UNITED STATES PATENT OFFICE.

ELMER E. KILMER, OF CLEVELAND, OHIO, ASSIGNOR TO H. C. WOODRUFF, OF CLEVELAND, OHIO.

PARTING-STRIP FOR WINDOWS.

1,123,196.

Specification of Letters Patent. Patented Dec. 29, 1914.

Application filed March 8, 1913. Serial No. 753,016.

To all whom it may concern:

Be it known that I, ELMER E. KILMER, citizen of the United States of America, residing at 7408 Cedar avenue, Cleveland, 5 in the county of Cuyahoga and State of Ohio, have invented certain new and useful Improvements in Parting-Strips for Windows, of which the following is a specification.

10 This invention relates to a new and useful improvement in window construction, more particularly to improvement in parting strips which separate the sashes.

The invention especially relates to that 15 kind of window construction in which the sashes swing vertically and then are removable from the window frames. In such construction, in order that the upper sash may be withdrawn from the window frame, the 20 lower portion of the parting strips must first be taken out and then be replaced after the upper sash is put back into the frame.

The invention, therefore, consists in a 25 parting strip of the construction hereinafter pointed out.

In the annexed drawings: Figure 1 represents a vertical section through a window frame showing the construction to which the invention is applied. Fig. 2, a detail perspective view of the invention and its application to the window frame. Fig. 3, a perspective view of the feature of the invention.

In these drawings, the numeral 1 designates a window frame having the upper 35 and lower sashes 2 and 3 and the parting strips 4 which are between the sashes. The parting strip 4 is made in three pieces, top and bottom portions 5 and 6, which are 40 rigidly secured in the window frame in the usual location and in the usual way and a middle removable portion 7. This portion 7 has the flat top 8 where it meets the flat bottom 9 of the top portion 5. The top 10 45 of the bottom portion 6 is cut off backwardly so that with the window frame this bottom portion forms a recess 11 back of the top 10 of the bottom portion. The top 10 has the horizontal portion 12 in front and 50 the slanting rearwardly downwardly inclined portion 13. The middle portion 7 of the parting strip 4 has its bottom end 14 made with the horizontal portion 15 corresponding with the horizontal portion 12 of 55 the bottom portion 6 of the parting strip 4

and the slanting portion 16 to correspond with the portion 13. This middle portion 7 is put into place as shown in Fig. 2. The slanting portion 16 is placed into the recess 11 against the portion 13 of the top 10 and the portion 15 resting on the portion 12 of the top 10, the end 8 fitting under the end 9 of the top portion 5 of the parting strip 4. In this position the parting strip is in place to separate the sashes. The check rail 17 60 at the bottom of the top sash 2 holds the top of portion 7 in place and the engagement of the bottom of the portion 7 in the recess holds the bottom of the portion 7 in place while the sash is in the frame, as the portion 7 extends above that part of the frame where the check rail 17 is when the upper sash is in its topmost position.

When it is desired to remove the sashes, the lower sash 3 is turned down, as shown 75 in Fig. 1, the upper sash 2 is then lowered. This brings the check rail 17 below the bottom end 14 of the portion 7 of the check rail, and this portion 7 may then be readily removed and the sash 2 withdrawn from the 80 frame. I am made aware that there have been parting strips made in several pieces with their meeting edges slanting and I make no claim thereto. But so far as I am aware there has not been devised previously 85 a parting strip in which there is a separable piece having one end resting in a recess in the window frame and held in place without any auxiliary fastening. I am further made aware that there has been patented a window frame having a removable part, the 90 ends of which fit into recesses in the window frame. But into this removable part the lower window sash fits and they are removable together, the recesses opening outwardly 95 so that the ends of the removable part of the window frame is pulled outwardly from the rest of the frame.

What I claim as my invention is:

1. A window parting strip consisting of 100 top, bottom and middle portions, the first two adapted to be secured in a window frame and the middle portion adapted to be removed from the window frame, the bottom end of the middle portion fitting behind 105 the top end of the bottom portion, the middle portion and the bottom portion together having a length greater than the distance between the bottom of the top sash and the bottom of the window frame, when the 110

top sash is at the top of the frame, whereby the lower part of the top sash will hold the middle portion of the parting strip in place.

2. A window parting strip, consisting of 5 top, bottom and middle portions, the top and bottom portions adapted to be secured in a window frame and the middle portion held loosely in and adapted to be removed from the window frame, the bottom portion 10 having a top made with a horizontal portion in front and a rearwardly downwardly inclined portion; the middle portion having its bottom end made with a horizontal portion corresponding with the horizontal portion 15 of the top of the bottom portion of the strip and a slanting portion corresponding with the inclined portion of the top of the

bottom portion of the strip, the bottom end of the middle portion of the strip fitting upon and behind the top of the bottom portion of the strip, the middle and the bottom portions of the strip having a length greater than the distance between the bottom of the top sash and the bottom of the window frame when the top sash is at the top of the 25 window frame, whereby the lower part of the top sash will hold the middle portion of the parting strip in place.

In testimony whereof I affix my signature in presence of two witnesses.

ELMER E. KILMER.
